SAUNA HUT OR THE LIKE

Arthur P. Pfeil, Williamsville, N.Y., assignor to Arrow
Tank Company, Inc., Buffalo, N.Y.

Filed Mar. 27, 1962, Ser. No. 69,459

Term of patent 3½ years

(Cl. D13—1)

FIG. 1 is a front perspective view of a sauna hut or the like showing my new design;

FIG. 2 is a rear perspective view thereof; and

FIG. 3 is a side elevational view thereof.

The side not shown is identical to the side shown in FIG. 3.

I claim:

The ornamental design for a sauna hut or the like, substantially as shown and described.
